UNITED STATES PATENT OFFICE.

THADDEUS J. LORDS AND GARFIELD P. LENNARTZ, OF CHICAGO, ILLINOIS, ASSIGNEES
TO SEARS, ROEBUCK AND CO., OF CHICAGO, ILLINOIS, A CORPORATION OF NEW
YORK.

ROOFING MACHINE.

Application filed November 5, 1920. Serial No. 421,910.

To all whom it may concern:

Be it known that we, THADDEUS J. LORDS and GARFIELD P. LENNARTZ, citizens of the United States, residing at Chicago, in the county of Cook and State of Illinois, have invented certain new and useful Improvements in Roofing Machines, of which the following is a specification.

Our invention relates to the manufacture of protective material for covering the roofs and walls of buildings, and more specifically to an improved machine for manufacturing roofing. Such roofing is ordinarily surfaced with ground slate or other weather resisting material, and roofing having a pattern formed thereon, so as to look like shingles or tile for instance, presents a much more attractive appearance than roofing having a uniform surface.

The object of our invention is to provide a machine for producing such roofing quickly and economically.

Further objects and advantages of our invention will become apparent as the description proceeds.

In the accompanying drawings, Figure 1 is a diagrammatic view of an entire roofing machine of which our improved surfacing device forms a part. Fig. 2 is an end view of the device itself, and Fig. 3 is a longitudinal section on the line 3—3 of Fig. 2. Fig. 4 is a transverse section of the device, and Fig. 5 is a fragmentary view of the inner stencil. Fig. 6 is a section taken on the line 6—6 of Fig. 5. Fig. 7 is a detail section on line 7—7 of Fig. 2.

In the embodiment of our invention selected for illustration, the paper P may be drawn from a suitable source of supply, such as a roll 10, and is first passed through take-up rollers 12. The upper rollers are movably mounted and may be lowered at a constant rate to permit the rest of the machine to receive paper at a constant rate without taking paper from the roll 10. This makes it possible when the end of a roll is reached for the workman to cement on the end of a new roll without stopping the entire machine. After passing over rollers 12 the paper passes over other rollers 14 into and out of a bath of tar, asphaltum or other suitable substance with which it is more or less thoroughly impregnated. From this bath it passes under a pipe 16 which

deposits material on the moving strip and between a stationary pair of rolls 17 by means of which the material is spread out into a smooth, uniform coating over the surface of the paper. Excess coating material may fall off the edges of the strip of paper and be collected in a suitable receptacle, not shown. The upper roller 17 is preferably made vertically adjustable for controlling the thickness of the coating spread on the paper. The foregoing elements being old and well known in the art and constituting no part of our present invention, more detailed disclosure of the same is deemed unnecessary.

Various combinations or sets of devices for applying ground material or surfacing to one or both sides of the roofing may act on the same after it passes through the roller 17. We have shown two such arrangements in Fig. 1, the one shown in full lines comprising means for passing the paper under a feeding device 18, around a large roller 20 which presses most of the surfacing deposited by the device 18 into the coating applied by pipe 16, another roller 19 employed merely for convenience in reversing the direction of the strip, and a final pair of rollers 21 which press the material carried by the strip a second time after the temperature of the strip has been considerably reduced from that prevailing adjacent the roller 20. A scraper blade 23 is preferably provided to direct surfacing in excess of what will adhere to the strip off the descending side of roller 20 into a receiving chute 25 to convey it back to the main supply. A hopper 27 is ordinarily positioned so as to coat the reverse side of the paper with ground material, usually fine powdered mica. The same plant may be employed to produce paper coated with fine powdered mica on both sides by passing the paper along the path shown in dotted lines to receive coatings of suitable material on both sides from other hoppers 27.

The device 18 for feeding surfacing material is illustrated more in detail in Figs. 2, 3 and 4. A pair of standards 24 and 26 support a stationary shaft 28 which in turn supports two spiders 30 and 32. A cylinder 34 is fastened at its ends to the spiders 30 and 32 completing the main framework of the machine. The cylinder 34 has a longitu-

dinal slot 36 beneath which the paper P is carried, passing over a support 38 suitably mounted on vertical bolts 40 adjustable in height by means of nuts 42.

5 Within the cylinder is a hopper comprising inclined plates 44 and 46 suitably reinforced by angle members 48 and cooperating with a feed roller 50 to hold the ground material with which the paper is to be surfaced, and deliver it at a uniform rate. The rate of discharge may be conveniently adjusted by means of a gate 52 in the nature of a slidable plate the position of which may be controlled by rotating a shaft 54 carrying pinions 56 meshing with racks 58 mounted on the plate 52. The clearance between the edge of the gate 52 and the roller 50 determines the rate of discharge, the material being carried out by 10 the roller and dropped between converging guide plates 60 which direct the stream of material through the slot 36. The supply of material in the hopper may be replenished through holes 62 in the upper portion of the cylinder. It will be seen that if the slot 36 were totally unobstructed the paper passing below the same would receive a uniform layer of ground material over its entire surface.

15 We have provided means for interrupting the flow of material through the slot 36 to produce a pattern on the paper. This means comprises in the present device, a pair of stencils 64 and 66 rotating inside and outside the cylinder 34 and cut so as to interrupt the flow of surfacing through the slot in such a way as to produce the desired pattern. The outer stencil 66 is driven at a surface speed practically identical with that 20 of the paper P and moves almost in contact with the paper. Each part of the stencil will therefore prevent the deposit of surfacing on the area which it covers as it passes by the slot, producing a sharply defined uncoated area. The inner stencil 64 is driven at the same rotary speed as the outer stencil so as to remain in perfect register therewith and functions to interrupt nearly all the material which must be diverted to produce the pattern, so that the outer stencil 66 merely functions to sharpen the outlines of the pattern. The longitudinally extending portions of the inner stencil 64, as clearly illustrated in Fig. 6, 25 are equipped with carriers 68 in the nature of small angle bars which catch the material interrupted and carry it up around the inside of the cylinder as shown in Fig. 4 to a position above the hopper where the inversion of the parts will allow the material to fall back again into the hopper. The accumulation of excess ground material in the bottom of the cylinder is thus effectively prevented.

30 As the strip passes around the roller 20

and is tipped into an approximately vertical position, particles of surfacing not yet pressed into the strip would naturally tend to fall from the edges of the covered areas into the adjacent uncovered areas and blur 70 the outlines of the pattern. To eliminate this tendency we provide means for applying a preliminary pressure to the strip before it has been tipped by movement around roller 20 to an angle steep enough to permit of such falling action. In Fig. 1 we have illustrated a roller 79 pressed against the lower side of roller 20, preferably by a counterweight such as 81. Rollers 21 and the mechanism receiving the strip therefrom ordinarily exert a considerable tension on the strip so that during its entire passage around roller 20 the strip is firmly pressed against the roller, but the use of roller 79 forces the material into place sufficiently to prevent subsequent blurring of the outlines during the passage of the strip over the upper portion of the roller 20. In changing over to use hoppers 27 roller 79 may obviously be shifted out of the way, or even removed entirely.

Any suitable power driven transmission may be employed to actuate the parts above described. We have illustrated a gear 70 on a longitudinally extending shaft 72, which 95 shaft carries two pinions 74 meshing with the outer gear teeth of two double gears at opposite ends of the cylinder, each double gear comprising a sleeve 76 having gears 78 and 80 formed at its ends. The gears 78 are also in mesh with gears 79 on the roller shaft 82 to drive the feed roller 50 and the inner gears 80 are each in mesh with intermediate drive pinions 84 (see Fig. 7) 100 which in turn engage internal teeth on rings 86 carried by the outer stencil. Short shafts 85 connect the pinions 84 for the outer stencil to similar pinions 87 driving the rings 88 which carry the inner stencil so that both stencils are driven at the same 105 rotary speed.

While we have illustrated and described in detail the preferred embodiment of our invention, it should be clearly understood that the disclosure is merely for purposes of illustration and that many modifications and variations will naturally occur to those skilled in the art. We aim in the subjoined claims to cover all such legitimate variations and modifications.

We claim as our invention:

1. In a device of the class described, a stationary element having a slot in its lower portion, means for moving a strip past below said slot, means for discharging a stream of material through said slot for coating said strip, and means above said slot for interrupting the flow of material to form a pattern on the strip.

2. In a device of the class described, a

stationary cylindrical structure having a slot in its lower portion, means for moving a strip past below said slot, a stencil moving outside said cylindrical structure having the same surface speed as the strip, and a stencil moving inside the structure having the same rotary speed as the outer stencil, said cylinder having apertures in its upper portion through which ground material 10 may be injected.

3. In a device of the class described, a stationary cylindrical structure having a slot in its lower portion, means for moving a strip past below said slot, a stencil moving 15 outside said cylindrical structure having the same surface speed as the strip, and a stencil moving inside the structure having the same rotary speed as the outer stencil.

4. In a device of the class described, a 20 stationary cylindrical structure having a slot in its lower portion, means for moving a strip past below said slot, a stencil moving outside said cylindrical structure having the same surface speed as the strip, and a stencil moving 25 inside the structure having the same rotary speed as the outer stencil, said inner stencil having means for conveying material from the lower portion of the cylinder to the upper portion and there 30 dropping it.

5. In a device of the class described, a moving stencil, means for discharging a stream of material through the lower part of said stencil, and means carried by said 35 stencil adapted to retain the material interrupted by the stencil in its movement and carry it around and up to the upper portion of the stencil.

6. In a device of the class described, a 40 rotating cylindrical stencil, storage means inside said stencil, means for rotating said stencil and for discharging a stream of material from said storage means through the lower part of said stencil, and carriers on said stencil adapted to retain material interrupted by said stencil and carry it up to the upper portion of the stencil where the inversion of the carriers will allow the material to fall back into the storage means.

50 7. In a device of the class described, spaced standards, a stationary shaft sup-

ported by said standards, a tubular structure stationarily supported by said shaft, said structure having a slot on its lower portion, means inside of said structure for 55 delivering a stream of material through said slot, and a tubular stencil rotatably supported on the outer periphery of said tubular structure, said stencil being constructed so as to intermittently shut off the flow of 60 material through said slot.

8. In a device of the class described, spaced standards, a stationary shaft supported at its ends by said standards, a tubular structure stationarily supported by said 15 shaft, and a tubular stencil rotatably supported in the inner periphery of said tubular structure.

9. In a device of the class described, a stationary cylindrical structure having a 70 slot in its lower portion, means for moving a strip past below said slot, a stencil moving outside said cylindrical structure and another stencil moving inside the structure, and means for delivering a stream of mate- 75 rial to fall through said slot.

10. In a device of the class described, a stationary cylindrical structure having a slot in its lower portion, means for moving a strip past below said slot, a stencil moving 80 outside said cylindrical structure and another stencil moving inside the structure, and means for delivering a stream of material to fall through said slot, said inner stencil having carriers for conveying material accumulating in the lower portion of the cylinder to the upper portion and there 85 dropping it.

11. In a device of the class described, spaced standards, a stationary shaft sup- 90 ported in said standards, a tubular member supported on said shaft, a stencil supported at the outer periphery of said member, a stencil supported at the inner periphery of said member, and means to produce relative movement between said member and 95 said stencils.

In testimony whereof we have hereunto set our hands.

THADDEUS J. LORDS.
GARFIELD P. LENNARTZ.
